CLAIM

The ornamental design for a device mount, as shown and described.

DESCRIPTION

FIG. 1 is a front perspective view of a device mount according to a first embodiment of our new design;

FIG. 2 is a front elevation view of the device mount of FIG. 1;

FIG. 3 is a rear elevation view of the device mount of FIG. 1;

FIG. 4 is a left-side elevation view of the device mount of FIG. 1;

FIG. 5 is a right-side elevation view of the device mount of FIG. 1;

FIG. 6 is a top plan view of the device mount of FIG. 1;

FIG. 7 is a bottom plan view of the device mount of FIG. 1;

FIG. 8 is a front perspective view of a device mount according to a second embodiment of our new design;

FIG. 9 is a front elevation view of the device mount of FIG. 8;

FIG. 10 is a rear elevation view of the device mount of FIG. 8;

FIG. 11 is a left-side elevation view of the device mount of FIG. 8;

FIG. 12 is a right-side elevation view of the device mount of FIG. 8;

FIG. 13 is a top plan view of the device mount of FIG. 8; and,

FIG. 14 is a bottom plan view of the device mount of FIG. 8.

The broken lines immediately adjacent to the shaded areas depict the bounds of the claimed design, while all other
